Inventor:

Otto Ballert

By *Paul Daniels, Jr.*
Attorney.

UNITED STATES PATENT OFFICE.

OTTO BALLERT, OF BERLIN, GERMANY.

CAR-BODY-TIPPING DEVICE.

Application filed April 25, 1924. Serial No. 703,975.

To all whom it may concern:

Be it known that I, OTTO BALLERT, a citizen of the German Republic, and residing at Berlin, Germany, have invented a certain 5 new and useful Improved Car-Body-Tipping Device, of which the following is a specification.

My invention relates to a tip-car of the type known as universal tip-car, the body 10 of which can be tipped rearwardly, as well as laterally by means of only one tipping device.

There are, among the tip-cars of this 15 known type, also such where the tipping member proper consists of a rack engaging the car-body below its centre of gravity, the rack being actuated by a cog-wheel gearing and this latter, together with a casing enclosing it, and with said rack, being so 20 arranged and supported as to be able to oscillate on a driving spindle lying parallel to the longitudinal axis of the car.

The object of the present invention is to 25 obviate a certain difficulty connected with car-body tipping devices of the before-mentioned kind, viz. such with rack and cog-wheel gearing, especially if the car is driven by the intermediary of a Cardan-gear. It is, with tip-cars of this kind very difficult 30 to house the rack, or racks, in such a manner that it does not, or they do not, interfere with the Cardan-shaft or with parts pertaining thereto. This difficulty is obviated in the present invention by using a 35 so-called double-jack instead of the simple rack-jack hitherto employed, the car-body lifting-member of the double jack being devised similarly to a crank-drive gearing or to a connecting-rod gearing, and the crank 40 or the connecting rod being actuated by a cog-wheel, or by a plurality of cog-wheels. The shaft, or shafts, of the cog-wheels as the case may be, move, up or down simultaneously with the revolution of the cog-wheel which is accomplished by means of 45 a pinion connected firmly with the shaft of the crank cog-wheel, which meshes with the teeth of a rack and moves it up or down according to the direction of rotation of said 50 crank cog-wheel.

My invention is illustrated by way of example in the accompanying drawings in 55 which Figure 1 is a side-view of the rear part of a motor freight tipping car provided with the improved tipping device, the

car-body being shown in two positions, viz. in its normal position in full lines, and rearwardly tipped in dotted lines; Figure 2 is a rear view of said car, the body being also in this figure shown in two positions, viz. in its normal position in full lines, and tilted laterally in dotted lines; Figure 3 is a side-view of the tipping device proper, drawn to an enlarged scale, the position of the uppermost parts of the figure (portion 60 of the car-body bottom and parts affixed thereto and connected therewith) corresponding to the position shown in dotted lines in Fig. 1; Figure 4 shows the same parts in the position corresponding to that 65 shown in full lines in Fig. 1; Figure 5 is a front-view of the same parts, and Figure 6 is a plan thereof.

1, Figs. 1 and 2, denotes the body of the car, and 7, Figs. 3-5, the bottom thereof, to 70 which is secured a body frame 6 carrying a connecting frame 4 provided with pivots 5 on which the frame 6 (with the car-body) can turn to one or the other side (Fig. 2, position shown in dotted lines). The frame 75 4 is connected to the upper ends of connecting rods 2 (Figs. 3-5), but this connection is an indirect one in that it is effected by the intermediary of springs 26 connected at their ends by bolts 27 with the frame 4, 80 and connected with the rods 2 by bolts 25 located in short vertical slots 4^a (Fig. 5) of the side-parts of the frame 4. The upper end of each connecting rod 2 engages a 85 vertical slot 4^b, the size of which is such that the rod 2 can assume an oblique position 90 relatively to the frame 4, as shown in Fig. 3. But the rods 2 can also be moved a trifle relatively to the slots 4^a, that is to say, the 95 bolts 25 can be moved a little up or down therein, as the case may be, the springs 26 being then slightly bent so as to turn from their straight shape (Fig. 3) into a slightly curved one (Fig. 4), or reversely.

There are two connecting rods 2, one on 100 the left of the frame 4, the other on the right thereof (Figs. 5 and 6), and each rod 2 is connected with a large cog-wheel 9 by means of a crank-pin 8. The two cog-wheels 9 are firmly connected with each 105 other by an axle 10, to which is firmly secured a smaller cog-wheel 11 meshing with a rack 12 hinged at the point 13 to a frame 14 which has a pivot 23 at its front end and a pivot 25 at its rear end, the two pivots 110

being supported in transverse members 22 forming parts of the super-structure of the car. The jack frame 14 serves also as carrier of a casing enclosing some of the parts forming the cog-wheel gearing.

The rack 12 is held in gear with the cog-wheel 11 by a sleeve 15 having a lateral extension enclosing the cog-wheel 11. The mechanism consisting of the cog-wheel 9, 10 the cog-wheel 11, the axle 10, and the sleeve 15, can be moved up and down along the rack 12 (compare Figs. 3 and 4) and is supported in every position by two arms 16 supported with their free ends on an axle 17 of a driving cog-wheel 18 which is constructed as a worm-wheel and meshes with a worm 18^a (shown in Figs. 4-6 in dotted lines) secured to the driving shaft 24 which extends into the gearing through the pivot 23 that is provided with a bore for this purpose.

On the axle or shaft 17 are two pinions 20 which mesh with the large cog-wheels 9 at any position of height of these latter (Figs. 3 and 4) owing to the connection of 25 the axle or shaft 17 with the axle 10 by the arms 16.

The manner of operation of the tipping device is as follows:

Supposing, the car-body be in its proper 30 normal or horizontal position, as in Figures 1 and 2 (position shown in full lines) and shall be tipped rearwardly or laterally, the shaft 24 is coupled with the motor of the car by means of a friction-clutch or any 35 other suitable clutch, in consequence whereof the worm-gearing 18^a/18 is rotated, as are, of course, also the shaft 17, the pinions 20, the large cog-wheels 9, the axle 10, and the cog-wheel 11, so that this latter climbs up- 40 wards along the rack 12 lifting with it the axle 10 and the large cog-wheels 9 from the normal position (Fig. 4) for instance into the position shown in Fig. 3. Owing, however, to the rotation of the large cog-wheels 45 9 their crank-pins 8 are raised, as are with them also the connecting-rods 2, and this motion is transmitted by the springs 26 to the car-body which now is tipped either rearwardly or laterally according to which of 50 the supporting means provided for holding it in normal position are released or checked, as the case may be. Tipping the car-body laterally is rendered possible by the provision of the frame 14 with its pivots 23 and 55 25 which are situated just in the longitudinal axis of the car (Fig. 2).

The succession of the motions is, of course, the reverse when the car-body is moved back into its initial position. When it has arrived 60 in its initial position, the crank-pins 8 are in their lowermost position, and in this position the springs 26 are slightly bent down so that the car-body is drawn or pressed onto its supports with a certain power whereby it 65 is retained securely in its position of rest.

I claim:

1. A car-body tipping-device, comprising, in combination: a jack-frame located below the car-body bottom, and pivots journally connected with said frame and being located 70 in the longitudinal axis of the car; an upwardly extending rack hinged to said frame; a cog-wheel meshing with said rack; means to keep the latter constantly in mesh with said cog-wheel; an axle connected firmly with the said cog-wheel and extending to both sides thereof; two larger cog-wheels secured to the ends of said axle and connected firmly therewith; two connecting-rods hinged at their lower ends to said larger 75 cog-wheels and at their upper ends to the car-body; means for carrying the said axle with its cog-wheels, and means for transmitting motion to the said two larger cog-wheels.

2. A car-body tipping-device, comprising, in combination: a jack-frame located below the car-body bottom, and pivots journally connected with said frame and being located 80 in the longitudinal axis of the car; an upwardly extending rack hinged to said frame; a cog-wheel meshing with said rack; means to keep the latter constantly in mesh with said cog-wheel; an axle connected firmly with the said cog-wheel and extending to both sides thereof; two larger cog-wheels secured to the ends of said axle and connected firmly therewith; two connecting-rods hinged at their lower ends to said larger 85 cog-wheels and at their upper ends to the car-body; a pair of arms carrying the said axle with its cog-wheels; a shaft carrying said arms at their other ends; pinions secured to this shaft and meshing with the large cog-wheels; a worm-wheel secured to the same shaft; a worm meshing with said worm-wheel and located below it, and a driving shaft located co-axially with the jack-frame pivots and having said worm affixed to it.

3. A car-body tipping-device, comprising, in combination: a jack-frame located below the car-body bottom, and pivots journally connected with said frame and being located 90 in the longitudinal axis of the car; an upwardly extending rack hinged to said frame; a cog-wheel meshing with said rack; means to keep the latter constantly in mesh with said cog-wheel; an axle connected firmly with the said cog-wheel and extending to both sides thereof; two larger cog-wheels secured to the ends of said axle and connected firmly therewith; two connecting-rods hinged at their lower ends directly to said 95 larger cog-wheels and at their upper ends indirectly to the car-body; springs forming the connecting means between said connecting-rods and the car-body and being connected at their ends with the car-body and in their middle with the said connecting-rods, 100 105 110 115 120 125 130

the length of these latter being such that said springs are slightly bent downwardly when the car-body is in its normal position; means for carrying the said axle with its cog-wheels, and means for transmitting motion to the said two larger cog-wheels.

4. A car-body tipping-device comprising, in combination: a jack-frame located below the car-body bottom, and pivots journally connected with said frame and being located in the longitudinal axis of the car; an upwardly extending rack hinged to said frame; a cog-wheel meshing with said rack; means to keep the latter constantly in mesh with said cog-wheel; an axle connected firmly with the said cog-wheel and extending to both sides thereof; two larger cog-wheels secured to the ends of said axle and connected firmly therewith; two connecting-rods hinged at their lower ends directly to said larger cog-wheels and at their upper ends indirectly to the car-body; springs forming the connecting means between said connecting-rods and the car-body and being connected at their ends with the car-body and in their middle with the said connecting-rods, the length of these latter being such that said springs are slightly bent downwardly when the car-body is in its normal position; a pair of arms carrying the said axle with its cog-wheels; a shaft carrying said arms at their other ends; pinions secured to this shaft and meshing with the large cog-wheels; a worm-wheel secured to the same shaft; a worm meshing with said worm-wheel and located below it, and a driving shaft located co-axially with the jack-frame pivots and having said worm affixed to it.

5. A vehicle comprising a car-body; a frame structure for supporting said car-body; a jack frame pivotally mounted on the chassis of the vehicle; a gear wheel mounted on the jack frame; a connecting rod secured at one end to the rear wheel and the other end to the frame structure; and means for rotating and elevating said gear wheel in order to elevate said frame structure by means of said connecting rod.

6. A vehicle comprising a car-body; a jack frame mounted on the chassis of the vehicle; a gear wheel mounted on the jack frame; a connecting rod secured at one end to the gear wheel and the other end to the car-body; and means for rotating and elevating said gear wheel in order to elevate said car-body by means of said connecting rod.

7. A vehicle comprising a car-body having a supporting frame structure; a jack frame pivotally mounted on the chassis of the vehicle; a gear wheel rotatably mounted on the jack frame; a connecting rod secured at one end adjacent the periphery of the gear wheel and the other end to the

supporting frame; and means in and on said jack frame for rotating and elevating said gear wheel in order to elevate said car-body by means of said connecting rod whereby the car-body may be tipped rearwardly and laterally relative to said vehicle due to the pivoted mounting of said jack frame.

8. A vehicle comprising a car-body having a supporting frame structure; a jack frame pivotally mounted on the chassis of the vehicle; a pair of gear wheels rotatably mounted on the jack frame; a connecting rod for each gear wheel secured at one end adjacent the periphery of the gear wheel and the other end to the supporting frame; and means in and on said jack frame for rotating and elevating said gear wheels in order to elevate said car-body by means of said connecting rods whereby the car-body may be tipped rearwardly and laterally relatively to said vehicle due to the pivotal mounting of said jack frame.

9. A car-body elevating device comprising a jack frame; a pair of arms pivotally mounted at one end in said jack frame; a pair of gear wheels mounted on the other ends of said arms; a toothed rack mounted on said jack frame; a cog-wheel associated with said rack and mounted to rotate with said gear wheels; a connecting rod for each gear wheel secured at one end to a side of the gear wheel and at the other end to the car body; and means in said jack frame for rotating said gear wheels whereby said gear wheels are elevated due to the cog-wheel and the rack to thus elevate the car-body by means of the connecting rods.

10. A car-body elevating device comprising a jack frame; an arm pivotally mounted at one end in said jack frame; a gear wheel mounted on the other end of said arm; a toothed rack mounted on said jack frame; a cog-wheel associated with said rack and mounted to rotate with said gear wheel; a connecting rod for the gear wheel secured at one end to a side of the gear wheel and at the other end to the car body; and means in said jack frame for rotating said gear wheel whereby said gear wheel is elevated due to the cog-wheel and the rack to thus elevate the car body by means of the connecting rod.

11. A car-body elevating device comprising a jack frame; a pair of arms pivotally mounted at one end in said jack frame; a pair of gear wheels mounted on the other ends of said arms; a toothed rack mounted on said jack frame; a cog-wheel associated with said rack and mounted to rotate with said gear wheels; a connecting rod for each gear wheel secured at one end to a side of the gear wheel and at the other end to the car body; and a gear and pinion mechanism in said jack frame for rotating said gear

- wheels whereby said gear wheels are elevated due to the cog-wheel and the rack to thus elevate the car body by means of the connecting rods.
- 5 12. A car-body elevating device comprising a jack frame having a shaft mounted therein; an axle mounted to swing around said jack frame; a pair of gear wheels mounted on said axle; a toothed rack mounted on said jack frame; a cog-wheel mounted on said axle and associated with said rack; a pair of pinions mounted on said shaft and meshing with said gear wheels; a connecting rod for each gear wheel secured at one end to a side 65 of the gear wheel and the other end to the car-body; and means in said jack frame for rotating said shaft whereby said gear wheels are elevated due to the cog-wheel and the rack and whereby said gear wheel will be rotated to thus elevate the car-body by 70 means of the connecting rod.
- 10 13. A car-body elevating device comprising a jack frame having a shaft mounted therein; an axle mounted to swing around said jack frame; a pair of gear wheels 75 mounted on said axle; a toothed rack mounted on said jack frame; a cog-wheel associated with said rack and mounted to rotate with said gear wheels; a connecting rod for each gear wheel secured near the circumference of each wheel at one end and to the car body at the other end; and means 80 for rotating said gear wheels to thus elevate the car-body by means of the connecting rods and for elevating said gear wheels by means of the cog-wheel and its toothed rack.
- 15 14. A car-body elevating device comprising a jack frame having a shaft mounted therein; an axle mounted to swing around said jack frame; a gear wheel mounted on said axle; a toothed rack mounted on said jack frame; a cog-wheel mounted on said 85 axle and associated with said rack; a pinion mounted on said shaft and meshing with said gear wheel; a connecting rod for said gear wheel secured at one end to a side of the gear wheel and the other end to the car-body; and means in said jack frame for rotating said shaft whereby said gear wheels are elevated 90 due to the cog-wheel and the rack and whereby said gear wheels will be rotated to thus elevate the car-body by means of the connecting rods.
- 20 15. A car-body elevating device comprising a jack frame having a shaft mounted therein; an axle mounted to swing around said jack frame; a gear wheel mounted on said axle; a toothed rack mounted on said jack frame; a cog-wheel mounted on said 95 axle and associated with said rack; a pinion mounted on said shaft and meshing with said gear wheel; a connecting rod for said gear wheel secured near the circumference of the wheel at one end and to the car body 100 at the other end; and means for rotating said gear wheel to thus elevate the car-body by means of the connecting rod and for elevating said gear wheel by means of the cog-wheel and its toothed rack.
- 25 16. A car-body elevating device comprising a jack frame having a shaft mounted therein; a pair of gear wheels mounted to swing around said shaft; a toothed rack mounted on said jack frame; a cog-wheel associated with said rack and mounted to rotate with said gear wheel; a connecting rod for said gear wheel secured near the circumference 105 of the wheel at one end and to the car body at the other end; and means for rotating said gear wheel to thus elevate the car-body by means of the connecting rod and for elevating said gear wheel by means of the cog-wheel and its toothed rack.
- 30 17. A car-body elevating device comprising a jack frame having a shaft mounted therein; a gear wheel mounted to swing around said shaft; a toothed rack mounted on said jack frame; a cog-wheel associated with said rack and mounted to rotate with said gear wheel; a connecting rod for said gear wheel secured near the circumference 110 of the wheel at one end and to the car body at the other end; and means for rotating said gear wheel to thus elevate the car-body by means of the connecting rod and for elevating said gear wheel by means of the cog-wheel and its toothed rack.
- 35 18. A car-body elevating device comprising a jack frame having a shaft mounted therein; a gear wheel mounted to swing around said shaft; a toothed rack mounted on said jack frame; a cog-wheel associated with said rack and mounted to rotate with said gear wheel; a connecting rod for said gear wheel secured near the circumference 115 of the wheel at one end and to the car body at the other end; and a set of pinions and gears for rotating said gear wheel to thus elevate the car-body by means of the connecting rod and for elevating said gear wheel by means of the cog-wheel and its toothed rack.
